UNITED STATES PATENT OFFICE.

MONROE A. COVER, OF OKMULGEE, OKLAHOMA.

PEN.

Application filed March 21, 1925. Serial No. 17,287.

To all whom it may concern:

Be it known that I, MONROE A. COVER, citizen of the United States, residing at Okmulgee, in the county of Okmulgee and State of Oklahoma, have invented certain new and useful Improvements in Pens, of which the following is a specification.

This invention relates to stationery and more particularly to an improved writing pen.

An important object of the invention is to provide a device of the above character whereby a pen may be firmly and securely retained in association with a holder.

A further object of the invention is the provision of a pen holder whereby the pen may be quickly and readily detached from the holder.

A still further object of the invention is the provision of a device of this character whereby the pen will be securely retained upon a holder against lateral movement.

A still further object of the invention is the provision of a pen holder of this character which is extremely simple, durable and can be placed upon the market at a relatively low cost.

Other objects and advantages of this invention will become apparent as the description progresses.

In the accompanying drawing, forming a part of this specification and in which like numerals are employed to designate corresponding parts throughout the same:

Figure 1 is a top plan view of my assembled device,

Figure 2 is a bottom plan view of the same, and

Figure 3 is a perspective view of the pen point.

In the drawing, wherein for the purpose of illustration is shown the preferred embodiment of my invention, the numeral 5 generally designates the holder or staff of my improved writing pen somewhat enlarged in the central portion and tapering toward the extremity. One extremity is provided with a comparatively large semi-spherical extension 6 while the other end is preferably tapered to a point as at 7.

A pen point generally indicated by the numeral 8 is adapted to connect with the holder 5 and comprises a common form of V-shaped writing pen 9 and a sleeve 10. This sleeve is provided with a tapered slit

11 whereby the pen point may be mounted in association with the extension of the holder. It can be readily noted from the construction of the sleeve member that same is expansible and normally smaller in diameter than the end of the holder.

When mounting the pen point upon the holder the sleeve 10 engages the end of the holder and is forced substantially thereon. The sleeve is then securely locked upon the holder by the provision of a continuous band 12 forcibly inserted over the sleeve 10 after the same has been placed tightly in engagement with the holder.

My improved device is provided to meet the demand for a writing pen wherein the pen point may be easily and securely attached to the holder and at the same time removed without difficulty. It is well known that the common forms of writing pens become tightly lodged in the holder after substantially long usage and are withdrawn with great difficulty. With my improved device the pen is readily mounted in association with the holder, sliding upon the gripping portion thereof by means of the sleeve 10. The retaining band 12 is then slid over the pen point and tightly engages with the expanded portion of the sleeve and holder preventing movement of the pen point. When it is desirable to change the point or for any other reason remove the same from the holder any implement can be used to force the retaining band from the pen point and in the same manner the sleeve from the holder, and the user need not touch the point with the fingers.

It is to be understood that the form of my invention herewith shown and described is to be taken as the preferred example of the same, and that various changes as to the shape, size and arrangement of parts may be resorted to without departing from the spirit of the invention, or the scope of the subjoined claims.

Having thus described my invention, I claim:

1. In a pen of the class described, a holder having a tapered extremity, a pen point having a sleeve formed thereon, and a retaining band adapted to retain the said sleeve in engagement with the said holder.

2. In a pen of the class described, a holder having tapered extremities, a pen point having a sleeve formed thereon, and a retain-

ing band slidable on the said sleeve and adapted to retain the same in engagement with the holder.

3. In a pen of the class described, a pen holder tapered toward the extremities, a pen including a writing point and an expansible sleeve member engageable with one end of the said holder, and retaining means including a circular band slidable upon the said sleeve for retaining same in association with the holder.

4. A pen of the class described including a holder tapered toward the extremities and provided with a comparatively large semi-spherical extension on one end, a pen point including a writing point, a slit sleeve formed thereon and engageable with the holder extension, and a retaining band slidable over the said sleeve and holder for retaining the pen firmly thereon.

5. In a pen of the class described, a pen holder tapered toward the extremities and provided with a semi-spherical extension on

one end thereof, a pen including a writing point and a slit sleeve slidable on one end of the holder, and a retaining band slidable over the said sleeve and adapted to firmly retain same in association with the holder.

6. The combination with a holder tapered toward the extremities, of a pen point including a writing point and an expansible sleeve engageable with the said holder, and a retaining band slidable upon the said sleeve for retaining same in association with the holder.

7. A pen of the class described including a holder tapered at one extremity to receive thereon a pen point, a pen point including a tapered writing point and a longitudinal sleeve having a tapered slot formed therein to permit yieldable connection with the holder, and a retaining band slidable over the said sleeve adapted to firmly retain the pen point in position on the holder.

In testimony whereof I affix my signature.
MONROE A. COVER.
